UNITED STATES PATENT OFFICE.

ABRAHAM W. PRATT, OF EUREKA, CALIFORNIA.

ELECTRIC-LIGHT-CORD TAKE-UP.

No. 906,286.

Specification of Letters Patent.

Patented Dec. 8, 1908.

Application filed February 15, 1908. Serial No. 416,987.

To all whom it may concern:

Be it known that I, ABRAHAM W. PRATT, a citizen of the United States, residing at Eureka, in the county of Humboldt and 5 State of California, have invented a new and useful Electric - Light - Cord Take - Up, of which the following is a specification.

This invention relates to hangers for electric lamps and other electrical devices and 10 has for its object to provide a comparatively simple and inexpensive device of this character by means of which the lamp may be conveniently supported at any desired height.

A further object of the invention is to 15 provide a hanger particularly designed for attachment to a ceiling cut-out or rosette, said hanger being provided with a spring actuated drum upon which the flexible suspension cord or cable is wound or unwound 20 as the lamp is raised or lowered.

A still further object of the invention is generally to improve this class of devices so 25 as to increase their utility, durability and efficiency as well as to reduce the cost of manufacture.

Further objects and advantages will appear in the following description, it being understood that various changes in form, proportions and minor details of construction 30 may be resorted to within the scope of the appended claims.

In the accompanying drawings forming a part of this specification: Figure 1 is a longitudinal sectional view of an electric lamp hanger constructed in accordance with my 35 invention. Fig. 2 is an end elevation of the same. Fig. 3 is a transverse sectional view. Fig. 4 is a detail perspective view of one of the bearing sleeves.

Similar numerals of reference indicate corresponding parts in all of the figures of the drawings.

The improved hanger forming the subject matter of the present invention includes 45 a supporting frame consisting of spaced longitudinal bars 5 and 6 connected by end pieces 7, the latter being provided with intermediate enlargements 7'.

Extending longitudinally of the frame is 50 a relatively stationary shaft 10 upon which is mounted for rotation a reel or drum forming a support for the adjacent terminals of a suspension cord or conductor 11 carrying an incandescent lamp 12. The reel or drum 55 comprises spaced heads or disks 13 connected by longitudinal rods 14, there being spaced

disks 15 disposed at the center of the reel and having peripheral notches or recesses 16 formed therein for the reception of the rods 14, as shown.

Secured to a lug or projection 17 on the shaft 10 is one end of a spiral spring 18 the opposite end of which is rigidly secured to the adjacent rod 14, as indicated at 19, the disks 15 being disposed on opposite sides of 60 the spring and serving to prevent springing or buckling of the latter.

Secured to the inner faces of the end pieces 7 are bearing sleeves 20 having annular flanges 21 for engagement with corresponding recesses formed in said end pieces, said bearing sleeves being reinforced and strengthened by the provision of filling blocks 23 preferably formed of wood, gutta percha or other insulating material and having angular recesses 23' formed therein for 70 the reception of the correspondingly squared terminals of the shaft 10, as shown.

Secured to the outer faces of the heads 13 are circular contact plates 23" which bear 80 against the sleeves or contact members 20 and complete the circuit through the lamp.

One end of each conductor 24 is extended through a longitudinal recess 25 formed in the upper longitudinal bar 5 of the supporting frame and is thence bent downwardly outside the adjacent end piece 7 and thence extended inwardly through an opening 25' in said end piece for contact with the rear face 26 of the adjacent bearing sleeve 20, 90 there being a pocket or chamber 27 formed in each end piece 7 for the reception of the terminals of the conductors 24, as shown. The conductors 24 are extended through an opening or aperture 28 in the center of the bar 5 for connection with a ceiling rosette of the usual construction. Secured to the disks or heads 13 are threaded pins 29 having their outer ends connected with the contact rings 23" and their inner ends connected 100 with the adjacent terminals of the suspension cord 11. It will thus be seen that the current has an unobstructed passage from the conductors 24 through the lamp 12 regardless of the position of the reel or drum. 105

As a means for holding the lamp in adjusted position there is provided a spring pressed bolt 29' having one end thereof provided with an enlarged head the contact face of which is curved or rounded for engagement with suitable sockets or depressions 30 formed in a metallic reinforcing 110

band 31. One end of the bolt 29' is arranged in a casing or housing 32 secured to the adjacent end piece 7 of the supporting frame, while the opposite end thereof extends through an opening in said end piece, as shown, there being a spring 33 interposed between the end piece 7 and the adjacent end of the casing 32 and operatively connected with the bolt for normally and yieldably holding the head of said bolt in engagement with one of the sockets in the reinforcing ring when the latter is at rest. It will thus be seen that when an initial downward pull is exerted on the suspension cord 11 to effect the adjustment of the lamp the head of the locking bolt will be forced laterally against the tension of the spring 33 out of engagement with the adjacent depression 30 and the spring 18 wound up or placed under tension. When the desired adjustment of the lamp is effected the spring 33 will force the head of the bolt 29 in engagement with the adjacent depression 30 and lock the lamp in adjusted position.

25 In order to elevate the lamp a slight pull is exerted on the conductor 11 which disengages the locking bolt in the manner before stated, the suspension cord or conductor 11 being wound on the reel by the tension of the 30 spring.

The lower longitudinal bar 6 is preferably formed with an elongated slot 34 for the reception of the suspension cord 11, this slot not only serving to guide the conductor 35 11 on the reel when the latter is rotated but also serving to center said suspension cord with respect to the reel.

From the foregoing description it will be seen that there is provided an extremely simple, inexpensive and efficient device admirably adapted for the attainment of the ends in view.

Having thus described the invention what is claimed is:

45 1. In a device of the class described, a supporting frame including end pieces having pockets formed therein, bearing sleeves secured to the end pieces at said pockets, said bearing sleeves constituting contacts, 50 a spring actuated reel mounted for rotation within the supporting frame and provided with annular contacts engaging the bearing sleeves, a conductor having its terminals disposed within the pockets and bearing 55 against said sleeves, and a suspension cord adapted to be wound on the reel and connected with the contacts of the latter.

2. In a device of the class described, a supporting frame including end pieces having 60 pockets formed therein, bearing sleeves secured to the end pieces at said pockets, filling blocks carried by the sleeves and having angular recesses formed therein, a stationary shaft seated in said recesses, a reel 65 mounted for rotation on the shaft, contacts

secured to the reel and engaging the bearing sleeves, a conductor having its terminals seated in the pockets and bearing against said sleeves, and a suspension cord adapted to be wound on the reel and electrically connected with the contacts on said reel.

3. In a device of the class described, a supporting frame including spaced end pieces having pockets formed therein, bearing sleeves secured to the end pieces at said 75 pockets and constituting contacts, filling blocks arranged within the sleeves and having angular recesses formed therein, a stationary shaft seated in said angular recesses, a spring actuated reel mounted for rotation 80 on the shaft, annular contact rings carried by the reel and engaging the sleeves, a conductor having its terminals seated within the pockets for engagement with the bearing sleeves, a suspension cord connected with 85 the annular contact plates, and a locking device carried by the frame and adapted to engage the reel for locking the latter against rotation.

4. In a device of the class described, a supporting frame, a spring actuated reel mounted for rotation in the frame, contacts carried by the frame and reel, respectively, a conductor engaging the contacts on the frame, a suspension cord adapted to be 90 wound on the reel and having its terminals connected with the contacts on the reel, a plate secured to one end of the reel and having depressions formed therein, and a locking bolt secured to the frame and adapted 100 to engage the depressions for locking the reel against rotation.

5. In a device of the class described, a supporting frame including longitudinal bars connected by end pieces, there being an aperture formed on one of the longitudinal bars, and an elongated slot in the other, bearing sleeves secured to the end pieces and constituting contacts, filling blocks carried by the bearing sleeves, a stationary shaft fastened in the filling blocks, a reel mounted for rotation on the shaft, annular contact plates engaging the bearing sleeves, a spring having one end thereof secured to the shaft and its opposite end fastened to the reel, a 115 conductor extending through the opening in one of the longitudinal bars of the frame with its terminals disposed in contact with the adjacent bearing sleeves, and a suspension cord having its terminals connected 120 with the annular contact plates of the reel.

6. In a device of the class described, a supporting frame including spaced longitudinal bars connected by end pieces having pockets formed therein, there being an opening formed in one of the bars, and a longitudinal slot in the other, bearing sleeves secured to the end pieces at said pockets, filling blocks carried by the sleeves, a stationary shaft anchored in the filling blocks, a reel 130

5 mounted for rotation on the shaft, annular contact plates secured to the reel and engaging the bearing sleeves, a spring having one end thereof secured to the shaft and its opposite end secured to the reel, a conductor projecting through the opening in said bar and having its terminals seated within the pockets for contact with the bearing sleeves, and a suspension cord adapted to be wound upon the reel and having its terminals connected with the annular plates of said reel.

10 7. In a device of the class described, a supporting frame, bearings secured to the opposite ends of the frame, a stationary shaft anchored in said frame, a reel mounted for rotation on the shaft and including spaced heads connected by longitudinal bars, an-

15 nular contact plates secured to the heads and engaging the bearings, a spring one end of which is secured to the shaft and the opposite end to one of the connecting bars of the reel, disks disposed on opposite sides of the spring, a conductor connected with the bearings, and a suspension cord adapted to be wound upon the reel and having its terminals connected with the annular contact plates on said reel.

20 In testimony that I claim the foregoing as my own, I have hereto affixed my signature in the presence of two witnesses.

ABRAHAM W. PRATT.
